UNITED STATES PATENT OFFICE.

SAMUEL T. HUGHES, OF CANONSBURG, PENNSYLVANIA.

MILL FOR ROLLING CAR-WHEELS.

SPECIFICATION forming part of Letters Patent No. 366,109, dated July 5, 1887.

Application filed April 5, 1887. Serial No. 233,736. (No model.)

To all whom it may concern:

Be it known that I, SAMUEL T. HUGHES, a citizen of the United States, residing at Canonsburg, in the county of Washington and State 5 of Pennsylvania, have invented certain new and useful Improvements in Mills for Rolling Car and other Wheels; and I do hereby declare the following to be a full, clear, and exact description of the invention, reference being had 10 to the accompanying drawings, which form part of this specification.

My invention has relation to rolling-mills or machinery for rolling car and other wheels from solid steel or iron blooms; and it consists 15 in the novel construction, combination, and arrangement of mechanism for feeding the rolls according as the bloom is reduced, and for producing the required pressure between the car-wheel and the shaping-rolls, in order to 20 effectively break down the bloom of steel or iron, as hereinafter described and claimed.

In the accompanying drawings, Figure 1 is a front elevation, partly in section, of a rolling-mill embodying my improvements. Fig. 25 2 is a vertical transverse section. Fig. 3 is a horizontal section or plan of the same, and Fig. 4 is a detail view.

The mill comprises two sets of housings, A A' B B', between which are located the rolls 30 and the mechanism for supporting the car-wheel which is being operated upon, and for intermittently raising and lowering it according to the progress of the work.

The rolls C C' are shaped to conform to the 35 contour of the face and rim of the wheel D, being provided with the convex heads c c and the flanges d d, the latter being adjustable, so as to adapt themselves to the spread of the wheel. The rolls rotate on horizontal axes, and are 40 provided with shafts E E', which are mounted in carriages, riders, or bearing-blocks F F', adjustable in the housings, and having journaled therein or abutting against the same the ends of vertical adjusting-screws f f', which 45 work in screw-boxes g g', fitted in the housings.

The screws f f' carry beveled pinions h h', which engage with a double-beveled gear-wheel, G, loosely mounted on the shaft of the roll and carrying a balance-wheel, G'.

50 G' is a lever-wheel attached to a beveled pinion or toothed wheel, G", working loosely upon the neck of the roll-shaft, and engaging

with the upper and lower pinions, h', of the screws f'.

G' is a collar, which is screwed or made fast 55 to the neck of the roll-shaft to retain the lever-wheel in gear with the pinions h'. The requisite adjustment of the rolls is effected through the medium of the lever-wheel and the gearing and screws connected therewith. 60

A² designates a horizontal beam or brace, having its ends dovetailed and let into the housings A B. In the middle part of said beam or brace is an opening, in which is loosely arranged a box, a, threaded interiorly for the 65 reception and working of a screw, J, having its lower end pointed or beveled to fit the conical recess j in the upper end of the mandrel J', which enters the eye of the car-wheel. The box a is formed with a ratchet-collar, a', with 70 which engages, when necessary, a pawl, a'', pivoted upon the beam or brace A². When the pawl and ratchet are in engagement, the box remains stationary, and hence any rotation of the screw-shaft J will cause the latter 75 to be adjusted vertically; but when the pawl and ratchet are disengaged the shaft J will turn without adjustment.

K is the forming-block upon which the car-wheel is mounted. Said block rests upon a 80 horizontal wheel, L, which is beveled and toothed on its under side, and which is fixed upon a vertical shaft, K', having its bearing in a recess, K², in a pillow-block, K³. On either side of said pillow-block are arranged beveled 85 toothed wheels M M', having short shafts m m' journaled in the pillow-block and in the housings A B, respectively. These wheels engage with and operate the wheel L, and are themselves engaged and operated by a beveled 90 toothed wheel, L², located back of the pillow-block and mounted on a horizontal shaft, L³, to which power is applied, and which has its bearings in said pillow-block and in a housing, L⁴, as shown. Upon the shafts of the 95 wheels M M' and turning therewith are the cam-wheels N N', of cylindrical form through nearly their entire circumference, but having the flat portions n n cut or provided thereon. These wheels constitute an essential feature of 100 my invention.

The operation of the mill is as follows: The bloom or casting from which the wheel is to be formed is mounted on the forming-block K

and the rolls adjusted down to the proper gage, while the wheels N N' lie with their flat portions under and facing the wheel L. The mill is now started, and as the wheels N N' turn their cylindrical surfaces come in contact with the face of the wheel L and raise the latter, thus producing a sufficient pressure of the car-wheel against the rolls to break down the bloom and render them effectively operative in shaping the wheel. As soon as the car-wheel has performed a single revolution, and the flat portions of the wheels N N' are again brought below the face of the wheel L, the forming-block K, gear-wheel L, and superposed car-wheel drop down to their first or starting point. The rolls are now adjusted or brought down into contact with the casting, and the operation being continued the casting is again raised into forcible pressure against the rolls and a second pass produced, and so on until the wheel is finished. As will be understood, the teeth of the gearing M M' are sufficiently long to permit of the required movement of the former without disengagement.

Having described my invention, what I claim, and desire to secure by Letters Patent, is—

1. In a mill for rolling car or other solid wheels, the combination, with the rolls and roll-shafts mounted in suitable housings and adjustable therein, of the forming-block K, toothed wheel L, and mechanism, substantially

as described, for rotating said wheel and forming-block, and for causing the same to intermittently rise and fall during the reducing operation, as set forth.

2. In a mill for rolling car or other wheels, the combination, with the frame-work or housings of the mill, of the roll C, shaft E, riders F F', adjusting screws f f', screw-boxes g g', 40 pinions h h', double gear-wheel G, and gear-wheel G³, substantially as described.

3. In a mill for rolling car or other wheels, the combination, with the adjustable working-rolls, of the forming-block K, horizontal toothed 45 wheel L, vertically adjustable upon its axis, vertical gear-wheels M M' L², and cam-wheels N N', substantially as and for the purpose described.

4. In a mill for rolling car and other wheels, 50 the combination, with the forming-block K and the mechanism for intermittently raising and lowering the same, of the mandrel J', the screw-shaft J, threaded box a, having ratchet-collar a', pawl a², and beam or brace A², substantially as described.

In testimony that I claim the foregoing I have hereunto set my hand this 23d day of March, 1887.

SAMUEL T. HUGHES.
